[57] CLAIM

The ornamental design for a nursing bottle holder, as shown and described.

DESCRIPTION

FIG. 1 is a perspective view of a nursing bottle holder showing my new design;

FIG. 2 is a top plan view thereof; and

FIG. 3 is a side elevational view thereof.

The nursing bottle which is shown by broken lines in FIG. 1 is shown for environmental purposes only, and does not form a portion of the invention.
